GUN-SIGHTING DEVICE

Frank E. Bliss, South Omaha, Nebr.

Application April 22, 1935, Serial No. 17,616

4 Claims. (Cl. 33—57)

This invention relates to a rear sight for firearms and more particularly for rifles.

One of the objects is to provide a transparent sight which will be disposed in close proximity to the eye of the user, through which the target, together with other objects and surrounding space, may be seen.

The invention includes a movable sight disposed rearwardly of the gun-barrel upon the inclined hand-gripping part of the gun-stock so that it will be near the trigger for quick adjustments at the time of firing.

The invention includes a gun-sight arranged for long-range shooting as well as short, and therefore it may have inclined slide movements longitudinally of the stock to higher or lower altitudes relative to the barrel, as may be required, and corresponding to the distance to a remote target.

It is an object to provide an inclined slide rear sight of such construction and arrangement of parts that it may be moved by the thumb of the user while a finger controls the trigger, this being of great advantage in instances when the target is moving swiftly to remote distances from the marksman and repeated firing is desired, the arrangement of said inclinedly movable sight also being provided with a graduated or indexed base for specific distances upon which the sight may slide for its adjustments.

With the foregoing objects in view and others to be mentioned herein, the invention consists of the new and useful construction, combination and arrangement of parts as described herein and claimed, and as illustrated in the accompanying drawing, it being understood that changes may be made in form, size and proportions as found to be of advantage, said changes being within the scope of the invention as claimed.

In the drawing, Fig. 1 is a side view of a rifle with the gun-sighting device mounted thereon.

Fig. 2 is an enlarged detail in side elevation, showing in solid lines, a slideable sight-lens in normal position on the hand-gripping portion of a gun stock for long range operations, and showing in dotted lines the position of same for short range operations.

Fig. 3 is a plan view of the parts shown in Fig. 2, and Fig. 4 is a transverse section on line 4—4 of Fig. 3.

Fig. 5 is a plan view of the base-plate for the movable lens.

Referring now to the drawing for a more particular description, the invention is shown and

described in connection with the barrel 7 and stock 8 of a rifle, the barrel having a front sight 9, and the stock, as usual, having an inclined hand-gripping portion 10 at its junction with the end of the barrel.

The improvement to be described relates simply to the rear sight together with its construction and advantages in operation.

Numerical 11 indicates an elongated base-plate which is disposed at an acute angle to the barrel 10 and is seated upon the upper portion of the inclined hand-gripping portion 10 of the stock.

This base-plate 11 may have any desired proportions, and it may have any suitable form in cross-section adapted to discharge its required functions.

For instance, since it provides an inclined slideway for the rear sight it should be disposed with its longitudinal axis in the vertical plane of the longitudinal axis of the gun-barrel, and for the purpose of maintaining this base-plate in a stationary position I have shown keepers 12 in its front end which secures it to the breech of the gun-barrel. However, other keepers may be used if desired for this purpose.

As best shown in Fig. 4 of the drawing the base-plate 11 is approximately of T-shape in cross-section. I provide a spring-controlled carrier-frame adapted to have slideable movements on the base-plate 11, said carrier-frame consisting simply of a flat strip or body-portion 13, best shown in Fig. 3, adapted to lie upon the base-plate 11, said body-portion 13 being provided with angular holder-prongs 14 arranged in pairs and adapted to slidably engage the edges of the base-plate 11 and having terminal portions 15 (Fig. 4) for engaging the lower sides of the ridges of the T-shaped base-plate 11.

As thus described the carrier-frame may have sliding movements upon and longitudinally of the base-plate and will be maintained thereon since the terminal parts 15 of said prongs 14 slidably engage the ridges as mentioned.

It will be noted that the lower end of the slideable carrier-frame is provided with a thumb piece 16, and therefore the user of the gun may, with a single hand, cause slideable movements of said carrier-frame between times of pressing the trigger, when repeatedly firing at moving game located at varying distances from the rifleman.

The carrier-frame is also provided with a socket-member consisting of a pair of upwardly projecting side-plates 17 for receiving the spindle 18 of the lens-frame 19, a pivot 20 which traverses the side-plates and spindle operating to permit

the spindle and lens-frame to have swinging movements forwardly or rearwardly to dispose the lens-frame upon the carrier frame when not in use, and to be disposed in a vertical position 5 when in use.

The transparent imperforate lens 21 is of disc-form and bears circular markings 22 centrally thereof as an aid to the marksman when aiming at a target, said element 22, while distinctly visible to the marksman, not operating as an obstruction to vision.

As shown in Fig. 5, the upper surface of the base-plate 11 is provided at longitudinal intervals with notches 23, and the front end of the 10 carrier-frame with a latch spring 24 best shown in Fig. 3, said spring being of such form that its end may engage in a selected notch for holding the carrier-frame in stationary relation relative to said base-plate, and in operation a marksman 15 may adjust the carrier-frame so that the projectile will accurately reach the target at specific selected distances.

The notches 23 are provided for the base-plate 11 or may be omitted as may be desired, said 20 notches being of advantage when the remote object is a stationary target. In instances when the target is movable these notches may be omitted.

The use of the herein described device will be 25 appreciated by game-hunters for the reason that adjustments may be quickly made of the sight on occasions when there are moving targets at varying distances, and several shots may be fired in succession before said moving targets are beyond range.

I claim as my invention,—

1. In a gun sighting device, a flat, metallic base-plate for a rigid mounting on the stock of the gun in a position inclined to the bore of the barrel, a metallic carrier-strip slidably mounted 40 on the base-plate and provided between its ends with an upright sight-member, and a longitudinally curved spring secured to the front end of the carrier-strip projecting forwardly to frictionally engage said base-plate and tending to 45 prevent sliding movements of the carrier, and a

thumb-piece secured to the carrier-strip for sliding said strip on the base-plate.

2. In a gun sighting device, an elongated base-plate of T-shape in cross-section provided transversely with notches and disposed on the stock 5 of the gun in a position inclined to the bore of the barrel, a metallic carrier-strip slidably engaging and having prongs bent downwardly for embracing the opposed sides of the base-plate, a socket on the carrier-strip, a transparent sight-member having a spindle pivotally mounted in the socket, and a spring normally in engagement with the base-plate and secured to the front end of the carrier-strip, said carrier-strip being provided at its rear end with a thumb-piece for moving said carrier to positions in which the free end of said spring engages in a selected one of said notches.

3. In a gun sighting device, a flat base-plate secured to the stock of the gun in a position inclined to the bore of the barrel and having transverse notches on its upper face, a carrier-strip 20 slidably mounted on the base-plate, a sight-bearing socket projecting above and secured to the carrier-strip, and a spring secured to the 25 carrier-strip and normally pressing against the face of the base-plate to engage in a selected notch, that part of the carrier-strip rearwardly of the sight-bearing socket being provided with a thumb-piece for moving said carrier-strip to 30 permit the free end of said spring to engage in a selected notch of said base-plate.

4. In a gun sighting device, an elongated base-plate secured to the stock of the gun in a position inclined to the bore of the barrel, an elongated 35 carrier-strip slidably disposed upon and having opposed prongs engaging the edges of the base-plate, an upright socket carried by the carrier-strip, a lens-holder pivotally mounted on the socket, and a spring carried by the carrier-strip 40 normally frictionally engaging the base-plate, that part of the carrier-strip to the rear of the socket being provided with a thumb-piece for moving said carrier to vary the elevation of the lens as the carrier moves along said base-plate. 45
